UNITED STATES PATENT OFFICE

HAROLD P. SLEEMAN, OF EAST LIVERPOOL, OHIO, ASSIGNOR TO THE R. THOMAS & SONS COMPANY, OF EAST LIVERPOOL, OHIO, A CORPORATION OF OHIO

INSULATOR

Application filed January 7, 1925. Serial No. 1,032.

My invention relates to insulators, and the object of my invention is to provide a post insulator, the insulating units of which are of the Hewlett or link type commonly used in suspension insulators. Specifically my invention contemplates a slight modification of the well known Hewlett insulator, and the provision of associated fittings adapted for cooperation therewith to build up a post insulator, so that the field of utility of insulators of this type is increased.

In the accompanying drawing—

Fig. 1 is a side elevation partially in section through a multi-unit insulator of the post type in which my invention is embodied in one form;

Fig. 2 is a section on the line 2—2, Fig. 3, showing a modified construction;

Fig. 3 is a section on the line 3—3, Fig. 2;

Fig. 4 is a plan on enlarged scale, of the screw bolt illustrated in Figs. 2 and 3; and

Fig. 5 is a section on the line 5—5, Fig. 4.

The Hewlett or link type insulator comprises a substantially spherical hub or body 15, from which projects a circumferential integral flange 16. The body of the insulator is pierced as usual by passages 17 and 18 at right angles to each other to accommodate the U-links 19 and 20 by which adjacent units 25 of the suspension string are loosely coupled together or to the terminal fittings. In these features the present insulator is of standard construction. My invention adapts this standard construction for strain insulators, to 30 a rigid post insulator.

For this purpose I provide between adjacent insulator units a spacer 21, here shown in the form of a tubular member, at the opposite ends of which are outwardly offset flanges 22 and 23, the offset ends of which are adapted to rest against the bodies of the adjacent insulators. To center the latter with respect to each other and to afford satisfactory seats for the flanges 22 and 23 of the spacer, I preferably form annular shoulders 24 and 25 in the opposed surfaces of the insulator bodies. The spacer is held in place and rigidly secured to the insulators by the U-shaped links 19 and 20. In the form shown in Fig. 1 the ends of 45 the links are threaded to receive the draw-up

nuts 26, and are passed through sockets 27 formed in the spacer flanges 22 and 23 on opposite diameters respectively.

The upper and lower, or terminal, fittings for the post insulator may be of any appropriate character. The base fitting 28, also of tubular form, is provided with a flange 29 adapted to rest against the shoulder 24 in the lower face of the lower insulator unit, and has a pair of sockets 30 to receive the ends of the link 19. The base flange 31 is apertured at appropriate points 32 for the accommodation of bolts or the like, by which the structure as a whole is secured to its support.

The fitting 33 at the opposite or upper end 55 of the structure, is provided with a flange 34 adapted to rest against the shoulder 25 on the upper surface of the body of the upper insulating unit, and is provided with sockets 35 to receive the opposite ends of the link 20. 70 A clevis 36, or other appropriate means, is provided on this fitting for attachment to the conductor supported by the insulator.

It will be realized that as many insulator units as desired may be utilized in building up 75 the post, and that the spacing and terminal hardware fittings may be of any appropriate type, so long as they are such as to cooperate with the U-shaped links which engage in the usual passages formed in the body of the insulator. Of course the structure may be supported upside down, i. e., with the clevis 36 at the lower end.

In the construction described, the links have threaded ends and associated draw-up 85 nuts. It is common, however, to utilize for loosely interconnecting Hewlett suspension insulator units, links of the construction shown in Fig. 3—that is to say, comprising a U-shaped bar 37 having anchoring heads 38 90 permanently secured to, or integral with, its opposite ends. The construction shown in Figs. 2—5 inclusive is adapted for use with a link of this type. For this purpose the flange 39 of the associated fitting, whether it be 95 spacer, such as 21, or terminal fitting, such as 28 or 33, is provided with a tapped hole 40 adapted to receive the shank of a hollow screw bolt 41, the head 42 of which is recessed 100 to afford a seat 43 for the accommodation of

the head 38 of the link. The bolt is also radially slotted at 44 to permit the shank of the link to be passed laterally into the longitudinal center of the screw. Adjacent the 5 tapped socket 40 of the flange 39 of the fitting is a plain passageway 45 of sufficient diameter to permit the link head 38 to pass freely therethrough. This passage communicates through a restricted channel 46 with the 10 tapped socket 40. When the radial slot 44 in the screw bolt is in register with the passage 46, it is possible to pass the shank of the link laterally into the screw bolt, so that when the latter is turned outward in its socket 15 40, the link head 31 is engaged in the seat 43. The engagement between the fitting and the insulator unit may be made firm by turning the screw nut further, while the lateral escape of the link from the screw is rendered 20 impossible by reason of the engagement of the link head 38 in the seat 43, even when the slot 44 of the screw registers with the passage 46 in the fitting flange. It is thus possible to utilize either type of link to secure 25 the rigid connection between the insulator unit and the associated fittings. When using the screw bolt type of Fig. 1, spring lock washers 47 are preferably placed beneath the nuts 26. These serve not only to hold 30 the nut against loosening, but also afford cushioning means which prevent excessive strains on the porcelain incident to uneven expansion or contraction on variations of temperature. The latter result can also be 35 attained in the second construction by springing the washers onto the shanks of the link beneath the heads 38 so that they lie between the latter and the seats 43 of the screw bolts 41.

40 The construction of the insulator and fittings is merely illustrative of my underlying conception, and is susceptible of various modifications without departure from what I claim as my invention.

45 I claim—

1. A post insulator comprising a pair of insulator units of the link type, a unitary tubular spacer extending therebetween, opposed U-links passing through the spaced insulator units, and means to engage the legs of the said links with the spacer and to unite the parts into a rigid whole.

2. In a post insulator having an insulator unit of the link type, a terminal fitting therefor comprising a tubular member having an outwardly offset annular flange adapted to rest against the body of the insulator, and a pair of sockets formed in said flange, on opposite sides of the axis of the fitting, and 55 adapted to receive the ends of a U-link passed through the insulator unit, together with means engaging the ends of the link with the fitting to hold the latter rigidly in position.

3. A combination adapted to be used in a 60 post or suspension insulator unit, comprising

a substantially spherical insulating body provided with a laterally projecting annular flange, said body being pierced in planes substantially at right angles to each other, by spaced, interlinked, arcuate passages which open respectively on opposite sides of said flange, together with seats formed by depressions in the spherical surface of said body on opposite sides of said flange and intersecting the mouths of the said passages, U links passing through said arcuate passages, a tubular unitary spacer having outwardly offset flanges, said spacer being adapted to rest upon either of the seats of said body and to be rigidly held thereon by a U link.

4. A post insulator comprising a series of insulator units each having a body pierced by spaced passages arranged in intersecting planes and having their entry openings faced respectively in opposite directions, unitary tubular metallic spacer elements between adjacent units, unitary metallic cap and base fittings for the respective terminal units of the insulator group, and oppositely-faced U-bolts arranged in the passages of each insulator and engaging the adjacent metallic members to secure the several parts into a rigid structure.

5. A post insulator comprising a series of insulator units each having a body pierced by spaced passages arranged in intersecting planes and having their entry openings faced respectively in opposite directions, unitary tubular metallic spacer elements between adjacent units, unitary metallic cap and base fittings for the respective terminal units of the insulator group, and readily-disengaged oppositely-faced U-bolts arranged in the passages of each insulator and engaging the adjacent hardware to secure the several parts into a rigid structure, and means readily accessible for clamping the U-bolts in position.

In testimony whereof I have signed my name to this specification.

HAROLD P. SLEEMAN.
